UNITED STATES PATENT OFFICE.

WILLIAM EDWARD BOEHCK, OF JERSEY CITY, NEW JERSEY, ASSIGNOR TO REVOLVATOR COMPANY, OF JERSEY CITY, NEW JERSEY, A CORPORATION OF NEW JERSEY.

HOISTING APPARATUS.

1,417,022.

Specification of Letters Patent. Patented May 23, 1922.

Application filed March 22, 1920. Serial No. 367,616.

To all whom it may concern:

Be it known that I, WILLIAM EDWARD BOEHCK, a citizen of Germany, residing at Jersey City, in the county of Hudson and

5 State of New Jersey, have invented certain new and useful Improvements in Hoisting Apparatus, of which the following is a specification, reference being had to the accompanying drawings.

10 This invention relates to improvements in hoisting apparatus, and particularly to improvements in hoists of the type adapted and designed for use in portable elevators (otherwise known as tiering-machines), that 15 is, to manually-operated hoists. An object of this invention is to provide a hoist in which the operator shall have the load at all times under his control and in which the load may be lowered by him with smoothness, ease, and safety to himself and to the hoist. Another object of this invention is to provide mechanism by which the power may be applied, in a hoisting-apparatus, with smoothness and may be kept under 20 absolute control at all times. Other features of this invention will become apparent as the description progresses.

In the drawings illustrating the principle of this invention and the best mode now 30 known to me of applying that principle, Fig. I is a sectional end (or side) view of so much of a manually-operated hoist as is necessary to illustrate this invention, the section being taken on the line I—I of Fig. II; Fig. II is a section on the line II—II, of Fig. I; and Fig. III is a detail, illustrating the drive-pinion in section and particularly the helical cam-surfaces thereon.

35 The drive-shaft *a* rotates in the bearings *b*, *b'*, which are supported by the structural frame-members *c* (shown conventionally at each end of the hoist). One end *a'* of the drive-shaft *a* is squared and thereby adapted to be engaged by a crank (not shown) for 40 turning the drive-shaft *a* by hand. Mounted on the latter is a friction-disk *d*, which is fastened thereto by means of a key *e*. That face of the friction-disk *d* which is opposed to the bearing *b*, is formed with an 45 annular recess *d'*, in which is fitted a split-ring *f* that is seated in an annular or circumferential groove *a''* formed in the drive-shaft *a*. It follows that, since the friction-disk *d* is keyed to the drive-shaft *a*, these two 50 members must rotate together; while the

friction-disk *d* is held from being pressed against the journal-box *b* by the interposition of the split-ring *f*. A sleeve *g* is slipped over the drive-shaft *a*, which is free to turn within the sleeve *g*. One end of the sleeve *g* abuts against a lateral face of the friction-disk *d*, while its other end is formed with an annular flange or integral disk *g'*. Mounted on the sleeve *g* is a sleeve *h*, within which the sleeve *g* fits and to which the same 60 is secured by the key *i*. One end of the sleeve *h* abuts against the flange or disk *g'* formed on the inner sleeve *g* at one end thereof, while the other end of the outer sleeve *h* is formed with an annular flange 65 or integral disk *h'*, a lateral face of which is opposed to a lateral face of the friction-disk *d*. On the outer sleeve *h*, there is mounted, free to turn, the hub *j'* of a ring-shaped brake-drum *j* having an overhanging 70 annular rim or flange *j''* that extends axially of the drive-shaft *a*, towards the disk or flange *h'* formed integral with the outer sleeve *h*. The interior cylindrical face of the rim or flange *j''* is formed with a series 75 of ratchet-teeth *k*, over which ride idly the toes of a pair of pawls *m* (Fig. I), the heels or butt-ends of which are mounted, free to turn, on the pivot-studs *n* that are screwed into and carried by the flange or disk *h'*. 80 The pivot-studs *n* are arranged diametrically opposite each other and the pawls *m* are pressed by springs *m'* towards the ratchet-teeth *k*. To one lateral face of the drive-pinion *o*, there is fastened, by a dowel-pin *o'*, a friction-disk *p*, a lateral face of which 85 is opposed to a lateral face of the flange or integral disk *g'* formed on one end of the inner sleeve *g*. On the other lateral face of the drive-pinion *o*, there are formed a pair 90 of helical cam-surfaces *r*, *r'*, which are diametrically opposed to each other and over which are arranged to travel the cam-rollers *s*, *s'*, respectively. Into a hole *q* that extends through the drive-shaft *a* at right-angles to 95 and intersecting the longitudinal axis thereof, there is driven a pin *t* both ends of which project beyond the drive-shaft *a*. The cam-rollers *s*, *s'*, are mounted, free to rotate, on these ends of the pin *t* and are secured in 100 place thereon by means of the nuts *u*. The friction-disk *p* and the drive-pinion *o* are mounted loosely on the drive-shaft *a*, which 105 may turn therein idly.

The brake-drum *j* is arranged to lie be- 110

between a pair of brake-jaws v of a brake-mechanism of the type described in United States Patent, No. 1,197,597, and illustrated in Fig. 6 thereof. While the load is being raised, the brake-jaws v are held firmly pressed against the rim or flange j'' of the brake-disk j against the tension of the coil-spring j^* , by turning the brake-controlling cam-shaft w in the proper direction, so as to cause the cams w' to bear against the cam-rollers w'' and force the upper ends of the brake-jaws v carrying the same, towards each other. In this way, the brake-drum j is held motionless.

The mode of operation of this hoisting apparatus may be briefly described as follows: Let it be assumed that a load is to be raised. A crank (not shown) is engaged with the squared end a' of the drive-shaft a , which is turned in the proper direction to raise the load. As the shaft a begins to turn, the friction-disk d and the pin t will be rotated with it, while the drive-pinion o , friction-disk p , and sleeves g , h , remain, for the time being, motionless, since these members last-named are loosely mounted on the drive-shaft. As the shaft a continues to turn, the cam-rollers s , s' , ride up on the helical cam-surfaces r , r' , and, since the pin t cannot be moved lengthwise of the shaft a , the drive-pinion o , friction-disk p , and sleeves g , h , will be slid along the shaft a , towards the friction-disk d , until the friction between the latter and the disk h' , between the disks g' , p , and between the cam surfaces r , r' , and the cam-rollers s , s' , has increased to a degree at which these parts are frictionally clutched with one another, whereupon the system rotates with the drive-shaft a . The brake-drum j is held motionless, however, by the brake-jaws v , while the sleeve h rotates within its hub j' and the clutching toe-ends of the spring-pressed pawls m mounted on the pawl-carrying disk h' ride idly over the internal ratchet-teeth k of the rim or flange j'' of the brake-disk j . When the shaft a ceases to be turned by the operator, retrograde rotation of the shaft a is prevented and the load is held in its raised position, by the interlocking engagement of the toe-ends of the pawls m with the internal ratchet-teeth k formed on the inner face of the rim j'' of the brake-disk j that is held fixed in position against rotation by the frictional pressure of the brake-jaws v . If it be desired to lower the load, this manoeuvre may be accomplished in either of two ways, both of which are controlled, to-wit: First, the operator may release the grip of the brake-jaws v by turning the cam-shaft w (and therewith the cams w') in such a direction that the coil-spring j^* is permitted to expand and force apart the upper ends of the brake-jaws v . The friction existing between the latter and the brake-disk flange j'' may be

so regulated that the load may be lowered as slowly as may be desired. Second, while maintaining the hold of the brake-jaws v on the brake-drum j so as to restrain all rotation of the latter, the operator may turn the drive-shaft a backwards, thereby causing the cam-rollers s , s' , to travel down (or into the hollow of) the cam-surfaces r , r' , and lessening the friction by which the disks p , g' , and the disks d , h' , are clutched together. This lessening of the friction between the parts just named will permit the weight of the load to overcome the resistance due to the friction, and the drive-pinion o will be turned backward by the pull of the load. When the operator desires to stop lowering away the load, he simply holds the drive-shaft a motionless, and the slight further rotation of the drive-pinion o causes the cam-rollers s , s' , to ride up on the thicker or more projecting part of the helical cam-surfaces r , r' , whereby the friction between the disks p , g' , and the disks d , h' , is increased to a point where independent rotation of the drive-pinion o is prevented and no rotation thereof can take place relatively to the drive-shaft a now held stationary.

Preferably the squared ends a' , w^* , of the drive-shaft a and brake cam-shaft w , respectively, will be made of the same size and shape, so that the same crank will fit both squared ends. When the operator desires to release the brake-jaws v so as to lower away the load by the first method hereinbefore explained, he will remove the crank from the squared end a' of the drive-shaft a , in order that he may use the crank to turn the brake cam-shaft w . Thus the operator will avoid the danger that would follow his leaving the crank on the drive-shaft a , which would rotate during the lowering of the load by the first method and would carry the crank around with it, thereby exposing the operator to being hit by the spinning crank.

I claim:

1. A hoisting apparatus including a drive-shaft; a pin angularly-disposed to and fixed upon the same; a drive-pinion mounted loose thereon and having one of its faces formed with a cam-surface over which the pin rubs; and a pawl-and-ratchet mechanism including a ratchet member and a pawl member, both of which members are mounted upon the drive-shaft; the drive-pinion and the pawl-and-ratchet mechanism being arranged to be pressed towards each other by the cam-action of the pin rubbing over the cam-surface, and the drive-pinion to be clutched frictionally to the drive-shaft.

2. A hoisting apparatus including a drive-shaft; a pin angularly-disposed to and fixed upon the same; a drive-pinion mounted loose thereon and having one of its faces

115
120
125
130

- formed with a cam-surface over which the pin rubs; a brake for preventing backward rotation of the drive-shaft during hoisting; and means for releasing the brake to lower 5 away the load while the drive-pinion remains clutched to the drive-shaft; the drive-pinion and the brake being arranged to be pressed towards each other by the cam-action of the pin rubbing over the cam-surface and 10 the drive-pinion to be clutched frictionally to the drive-shaft.
3. A hoisting apparatus including a drive-shaft; a friction-disk mounted fast thereon; a drive-pinion mounted loose upon the drive-shaft; means for forcing the drive-pinion lengthwise along the drive-shaft towards the friction-disk and clutching the drive-pinion frictionally to the drive-shaft; a brake for preventing backward rotation of the drive-shaft during hoisting; and means for releasing 15 the brake to lower away the load while the drive-pinion remains clutched to the drive-shaft.
4. A hoisting apparatus including a drive-shaft; a friction-disk mounted fast thereon; a brake member for preventing backward rotation of the drive-shaft during hoisting; teeth formed on said brake member; a pawl-carrying member loosely mounted on said 20 drive-shaft; a pawl carried by said pawl-carrying member and arranged to engage said teeth during backward rotation of the drive-shaft; a drive-pinion loosely mounted on the drive-shaft; means for forcing the 25 drive-pinion and pawl-carrying member lengthwise along the drive-shaft towards the friction-disk and clutching the drive-pinion and pawl-carrying member frictionally to the drive-shaft; and mechanism for releasing the brake member to lower away the load while the drive-pinion remains clutched to the drive-shaft.
5. A hoisting apparatus including a drive-shaft; a friction-disk mounted fast thereon; a brake-drum loosely mounted on the drive-shaft; teeth formed on the brake-drum; brake-jaws for holding the brake-drum against rotation; a pawl-carrying member loosely mounted on the drive-shaft; a pawl carried by said member and arranged to engage 30 said teeth during backward rotation of the drive-shaft; a drive-pinion loosely mounted on the drive-shaft; means for forcing the drive-pinion and pawl-carrying member lengthwise along the drive-shaft towards the friction-disk and clutching the drive-pinion and pawl-carrying member frictionally to the drive-shaft; and mechanism for releasing the grip of the brake-jaws on the brake-drum to lower away the load 35 while the drive-pinion remains clutched to the drive-shaft.
6. A hoisting apparatus including a drive-shaft; a friction-disk mounted fast thereon; a brake loosely mounted on the drive-shaft; a sleeve loosely mounted on the latter and interlocked with the brake; a drive-pinion loosely mounted on the drive-shaft; means for forcing the drive-pinion and sleeve lengthwise along the drive-shaft towards the 40 friction-disk and clutching the drive-pinion and sleeve frictionally to the drive-shaft; and mechanism for releasing the brake to lower away the load while the drive-pinion remains clutched to the drive-shaft.

Signed at the city of Jersey City, in the county of Hudson and State of New Jersey, this thirteenth day of March, 1920, in the presence of the two undersigned witnesses.

WILLIAM EDWARD BOEHCK.
